UNITED STATES PATENT OFFICE.

HAROLD L. HAINES, OF ANN ARBOR, MICHIGAN, ASSIGNOR TO ECONOMY BALER COMPANY, OF ANN ARBOR, MICHIGAN, A CORPORATION OF MICHIGAN.

RECEPTACLE.

Application filed April 14, 1924. Serial No. 706,557.

The invention relates to receptacles and more particularly to the self-closing type and has for an object improved apparatus for closing a door of the receptacle. Other 5 objects of the invention reside in the novel features of construction and combinations and arrangements of parts as more fully hereinafter set forth.

In the drawings:

10 Figure 1 is a side elevation, partly broken away, of a receptacle embodying my invention;

Figure 2 is a bottom plan view of the receptacle top;

15 Figure 3 is a side elevation, partly broken away, of a modified construction of receptacle;

Figure 4 is a bottom plan view of the top thereof.

20 1 is the body of the receptacle and 2 the top having upwardly and inwardly inclined sides. 3 and 4 are inwardly opening doors hinged at their upper edges at 5 and 6 respectively to the top and serving to close

25 openings in opposite sides thereof. These doors are limited in their outward movements by flanges 7 and 8 which respectively overlie the doors when in closed position.

30 9 and 10 are gravitating links or arms which are preferably pivotally connected at their outer ends to the doors 3 and 4 respectively near the lower edges of the latter, and 11 is a wall depending from the top 2 midway between the doors and forming a common abutment for the inner ends of the links.

35 The length of each link is such that its inner end is located sufficiently above its outer end with the door in closed position that when the door is swung inwardly, the inner end of the link may ride upwardly over the wall.

40 As shown in Figure 2, the inner end of each link is provided with a pair of rolls 12 mounted thereon and on opposite sides 45 thereof, these rolls being engageable with the wall 11. These rolls are preferably guided by means of a depending channel bar 13, the base of which forms part of the wall 11, and the sides of which are at the ends of 50 the rolls, these sides preferably terminating in inturned flanges 14 engageable with the

portions of the rolls opposite the base of the channel. The bases of the two channels are secured at their upper ends to the top 2 by suitable means such as the angle bars 15. 55

As shown in the modified construction of receptacle in Figures 3 and 4, the doors for closing the openings in the opposite sides of the receptacle are normally closed by the links or arms 16 which operate in the same 60 manner as the links shown in Figures 1 and 2. These links or arms, however, are arranged in pairs and have between their inner ends the rolls 17 which are engageable with the wall 18 depending from the top. For holding the rolls from disengagement from the wall 18, I have provided the strap 19 having a base portion 20 preferably secured to the lower end of the wall 18, side portions 21 extending parallel to the wall 18 and on the 65 opposite sides of the rolls 17 and the top portion 22 which is secured to the top of the receptacle. This strip is located between the links and as a consequence prevents lateral 70 displacement thereof. 75

From the above description it will be readily seen that I have provided a receptacle of the self-closing type in which the door for closing an opening thereof is moved to closed position by a very simple mechanism; and that the thrust for moving the door to closed position increases as the door approaches closed position. It will also be seen that the mechanism for closing one door operates independently of the mechanism for 85 closing another door.

What I claim as my invention is:

1. The combination of a receptacle having an opening, an inwardly opening door serving to close said opening, an abutment with- 90 in said receptacle, and a gravitating link for closing said door, said link having one end connected with said door and the other end cooperating with said abutment, and a roll upon said last-mentioned end and en- 95 gageable with said abutment.

2. The combination of a receptacle having a top and an opening, an inwardly opening door pivoted upon said receptacle and serv- 100 ing to close said opening, a link pivotally connected with said door for closing the same, and a member depending from said

top and provided with means for retaining the free end of said link in engagement therewith.

3. The combination of a receptacle having an opening, an inwardly opening door pivoted upon said receptacle and serving to close said opening, a link pivotally connected to said door and serving to urge said door

closed, a channel within said receptacle and opening toward said door, the sides of said channel terminating in inturned flanges, and an enlargement upon the free end of said link engageable in said channel and guided thereby.

In testimony whereof I affix my signature.

HAROLD L. HAINES.
